Inventor:
Ernest R. Falkenberg
By Drydenforth, Lee, Critten and Niles,
Attorneys.

UNITED STATES PATENT OFFICE.

ERNEST R. FALKENBERG, OF CLEVELAND, OHIO.

PLAITED DRAPERY.

Application filed June 10, 1926. Serial No. 115,035.

My object, generally stated, is to simplify, and greatly reduce the cost of, the making of plaited draperies, especially in the matter of providing on the draperies the necessary means whereby the draperies may be suspended, in the desired position, from the supporting rods therefor.

Referring to the accompanying drawings:—

10 Figure 1 is a broken view of one end of a pole for supporting a drapery, the pole being shown as equipped with a drapery-hanger, which in practice would be provided of a number corresponding with the number of plaits provided on the drapery. Figure 2 is a broken perspective view of the upper edge portion of a plaited drapery constructed in accordance with my invention. Figure 3 is a similar view showing the drapery in the course of producing one of the similar plaits; and Figure 4, a broken perspective view of a modification of my invention, the pole being shown by dotted lines.

25 Referring first to Figure 1, which shows, merely by way of example, one of the many forms of hanger devices in connection with which a drapery constructed in accordance with my invention may be used, the drapery-supporting pole is represented at 5 and would be secured in any desirable way, across the window, or other opening, or area, at which the draperies are to extend. Mounted on the pole 5 are a series of drapery

30 hangers, one only of which is shown, these hangers being provided of a number corresponding with the number of points at which the drapery is to be supported. The form of hanger shown comprises a pair of bars 6

40 connected together by a shaft 7 carrying rollers 8, at which the hanger rests upon the pole 5, the lower ends of the bars 6 being deflected inwardly toward the center of the pole 5 and thence upwardly and outwardly

45 as shown, at which portions the upwardly opening notches 9 are provided at opposite sides of the pole, the upper extremities of the bars 6 containing upwardly opening notches 10. The notches 9 and 10 are provided for receiving the drapery-supporting devices carried by the draperies, and provided, as for example, of button form, to hold the draperies located at opposite sides of the

50 pole, in the desired position in which the upper edges of the draperies extend above, and cover, the drapery hangers.

In the plaiting of the drapery, in accordance with the preferred embodiment of my invention, the material from which the drapery is to be formed, is folded upon itself at intervals, corresponding with the number of plaits to be formed, and pieces of tape, one of which is represented at 11, are inserted between the opposing portions of the folds, as for example to the position shown in Fig. 3, and the folded portions of the drapery then stitched, as for example along the lines represented at 12, this stitching extending through the folded portions of the drapery and through the tape 11. The stitching 12 is located remotely from the folded edge portions 13 of the drapery, and serves not only to define the plait-forming portions of the drapery and hold the plaited portions in position, but also to hold the tape in place, the latter extending rearwardly beyond the plaits, as shown. After stitching the drapery as described, the folded portions beyond the stitching are pressed down to the position shown in Fig. 2, to form the plaits 14 as represented by the plait 14 in this figure.

It is intended that the drapery be supported from the tape 11, and in accordance with the showing in Figure 1 at two points thereon, as for example by the buttons 15 and 16 provided on the tape and adapted to hook into the notches 9 and 10 respectively in the hanger. The drapery may be supported from the tape in any other desirable way however.

In practice it is preferred that the tape be preliminarily prepared, as for example by securing the buttons 15 and 16 thereto, before assembly with the main portion of the drapery, as this makes for great economy and facilitates the production of the finished article. If desired the tape, with the buttons thereon, or otherwise preliminarily provided with supporting means, may be supplied to the manufacturers of draperies and in the manufacture of the draperies the tape be cut into the desired lengths for use.

Referring to the construction shown in Fig. 4, the tape 11, instead of being equipped with buttons for co-operating with a hanger like that shown in Fig. 1, is provided with a ring, represented at 17, and sewed by the thread represented at 18 to the free edge of the tape 11. In this construction the drapery would be supported on the pole, represented at 5, direct from the ring 17 at each plait 14, these rings, if desired, being secured

to the tape 11, preferably provided in long lengths, to be cut into pieces, before being sewed into the plait-forming portions.

It will be manifest from the foregoing 5 that particularly by securing the tape 11 in place by the same stitching which defines the plaited portions, the labor involved in the producing of the plaited drapery, ready for hanging, is reduced to the minimum, 10 and thus the cost of producing such draperies is greatly minimized.

While I have illustrated and described a particular construction embodying my invention, and have described a particular way 15 of producing a plaited drapery in accordance with my invention, I do not wish to be understood as intending to limit it hereto as the structure may be variously modified and altered and the manner of constructing it 20 variously modified without departing from the spirit of my invention.

What I claim as new, and desire to secure by Letters Patent, is:

1. A drapery having portions thereof 25 folded to form a plait, tape extending lengthwise of, and adjacent to, said plaited portion, and means common to said plait-forming portions and to said tape for holding said plait-forming portions in position and said tape in place.

2. A drapery having portions thereof folded to form a plait, tape extending lengthwise of said plait-forming portions and into the space between the inner portions thereof, and means common to said plait-forming 35 portions and to said tape for holding said plait-forming portions in position and said tape in place.

3. A drapery having portions thereof folded to form a plait, tape extending lengthwise of, and adjacent to, said plaited portion, and stitching extending through said plait-forming portions and said tape for holding said plait-forming portions in position and said tape in place. 40

4. A drapery having portions thereof folded to form a plait, tape extending lengthwise of said plait and into the space between the inner portions thereof, and stitching extending through said plait-forming portions and said tape for holding said plait-forming portions in position and said tape in place. 45

5. A drapery having portions thereof folded to form a plait, tape provided with a support-engaging portion and extending lengthwise of, and adjacent to, said plaited portion, and means common to said plait-forming portions and to said tape for holding said plait-forming portions in position and said tape in place. 50

6. A drapery having portions thereof folded to form a plait, tape provided with a suspending device and extending lengthwise of, and adjacent to, said plaited portion, and means common to said plait-forming portions and to said tape for holding said plait-forming portions in position and said tape in place. 55

7. A drapery having portions thereof folded to form a plait, tape provided with a preliminarily applied support-engaging portion and extending lengthwise of said plaited portion, and means securing said tape to the drapery. 60

ERNEST R. FALKENBERG.
